UNITED STATES PATENT OFFICE.

SIGMUND L. GOLDMAN, OF CHICAGO, ILLINOIS, ASSIGNOR TO E. GOLDMAN & CO., INC., OF CHICAGO, ILLINOIS, A CORPORATION OF ILLINOIS.

BOTTLE-SOAKING MACHINE.

No. 920,564.

Specification of Letters Patent.

Patented May 4, 1909.

Application filed February 4, 1908. Serial No. 414,183.

To all whom it may concern:

Be it known that I, SIGMUND L. GOLDMAN, a citizen of the United States, residing at Chicago, in the county of Cook and State of Illinois, have invented a new and useful Improvement in Bottle-Soaking Machines, of which the following is a specification.

This invention relates to improvements in the class of apparatus for soaking bottles to remove their labels and cleanse them externally and internally with the soaking water, and involving, as the generally stated construction, a water-holding tank containing a vertically-traveling endless carrier on which are supported receptacles for holding the bottles, the apparatus being adapted to be loaded at one side thereof and the discharge taking place at the opposite side.

In the accompanying drawings, Figure 1 shows the apparatus by a view in side elevation; Fig. 2 is an enlarged view of the same in central cross-sectional elevation; Fig. 3, a plan view of the driving worm-gear, but omitting the worm-wheels; Fig. 4, a section on line A, Fig. 3, showing the worm-wheels; Fig. 5, a broken plan view of one of the similar bottle-crates; Fig. 6, a broken face-view of the same; Fig. 7, a broken section on line B, Fig. 5, and Fig. 8, a section on line C, Fig. 5; Figs. 9, 10, 11 and 12 are diagrammatic views, each presenting an end of a bottle-crate, the figures successively showing the crate in the position of approaching the gate-opening cam, of engaging the cam to open the spring-closed gate, of traveling along the cam-plate to maintain the gate open, and of clearing the upper end of the cam-plate to permit closure of the gate; Fig. 13, a broken enlarged section on line D, Fig. 1, showing the preferred construction of agitator for the water in the soaker-tank; Fig. 14, a section on line E, Fig. 13; Fig. 15, a section on line F; Fig. 16, through the bottle receiving and rinsing trough and the adjustable guide-chute which leads thereto from the soaker; Fig. 16, a broken section of the same taken on line G, Fig. 1 or Fig. 15, and Fig. 17, a diagrammatic view in perspective showing in unassembled relation the bottle-chute and the means provided for adjusting its proximity, its height and its angle of inclination relative to the soaker-tank.

The soaker-tank 18 is represented in rectangular shape and as having on one end an overflow 19 near the top, a covered manhole

20 and an emptying outlet 21 near the bottom, and a water-circulating pipe 22 communicating at its ends, respectively, with the lower and upper parts of the tank and containing an ordinary jet-pump indicated at 23, to which leads a valved steam-supply pipe 24 for driving the pump to circulate the water and for heating the water to maintain it at the proper temperature.

A trough 25, for receiving the bottles discharged from the soaker and rinsing them, is stably supported to extend from the front or delivery side of the tank 18 and is shown to be provided in one end with an overflow 26 and an emptying outlet 27, and to contain, for the purpose hereinafter explained, an open or grate-like false bottom (Figs. 15 and 16) shown to be formed of rectangular supports 28 having feet secured to the bottom of the trough and affording bearings for the ends of spaced rods 29 extending between them. Similar upright rigid frame-members 30, 31, flanged on the upper ends, rise from the flanged tops of the tank-ends and afford bearings for parts hereinafter described. On the member 30 are the two similar vertical angle-bars 32 affording guides for an oil-box formed as a single casting having the section 33 with the section 34 extending below it at one end and at a right-angle thereto, the two sections intercommunicating. In the base of the section 33 is journaled a worm-shaft 35 (Figs. 3 and 4) carrying on one end the worm-wheel 37 in the box-section 34, the worm on this shaft meshing with a worm-wheel 38 on an end of a shaft 39 journaled at one end in a bearing 39^a forming a part of the casting containing the oil-box members, and at its opposite end in a similar vertically adjustable bearing 39^b (Fig. 2).

A worm-shaft 40 is journaled in bearings in the box-section 34 to extend at a right-angle to the shaft 35 and mesh with the worm-wheel 37 thereon. The shaft 40 is the drive-shaft and carries on its outer end a belt-pulley 41 and adjacent to the latter a sprocket-wheel 42. The vertical adjustment of the shaft 39 is for taking up slack in the endless chains, hereinafter described, and is effected at each end by suitable means shown at one end in Fig. 1 as a bolt 43 passing through the top-flange of the frame-member 30, the opposite threaded end of the bolt working in the bearing of the shaft 39, whereby turning in one direction or the other

the adjusting bolts will raise or lower the drive-shaft and, incidentally, the oil-box and worm-gears correspondingly.

An agitator-shaft 44 is journaled in suitable bearings on the ends of the tank (Figs. 13 and 14) and carries on one end a sprocket-wheel 45 having the short-chain connection 46 with the sprocket 42. The agitator comprises, as its preferred construction, brackets 47 bolted at intervals to the shaft 44 to extend transversely thereof, with paddle-blades 48 extending parallel with the shaft at its opposite sides, but spaced therefrom and bolted, respectively, to the oppositely facing surfaces of the brackets.

At the inner sides of the frame-members 30, 31 are secured on the shaft 39 like sprocket-wheels 49, and similar sprocket-wheels, one of which is indicated at 50 in Fig. 1, are correspondingly provided on a shaft 51 journaled in suitable bearings on the opposite ends of the tank, the vertically alining members of each pair of these sprockets being connected by an endless chain 52. Extending at intervals between these chains, which form an endless rack-carrier, and permanently fastened to them, are the similar bottle-racks 53, the construction of which forms the principal feature of this invention. At the front or delivery side of the machine there is secured, to extend vertically along the adjacent edge of each frame-member 30 and 31, a cam-plate 54 having its lower end deflected outwardly or forwardly at a right-angle to form a cam 54^a, and its upper end inclined forwardly, as shown at 54^b, for the purpose hereinafter explained. Other cam-plates 54 are provided to extend vertically along the rear edges of the frame-members at the loading side of the machine and are like the cam-plates on the opposite side of the machine except that the cams 54^a project rearwardly and are on the upper ends of the bars and that the inclined end-sections 54^b are lowermost and extend rearwardly.

The construction of the bottle-rack, most clearly indicated in Figs. 5 to 8 inclusive, is the following: Between two similar head-forming end-plates 55, carrying perforated ears 55^a through which they are rigidly bolted to the opposite chains 52, extend, suitably spaced apart and rigidly fastened to the heads and reinforced transversely by the rods 56, similar partitions or shelves 57, of which three are shown containing alining openings 58 to admit, for support on the shelves, the bodies of bottles to be soaked. At the rear side of the rack is provided the stop for the bottles, shown as a pair of parallel bars 59 extending between the heads 55, to which they are fastened like the shelves, these bars being reinforced by transverse rods 60 connecting them with the adjacent shelf. On the opposite or front side of the

rack is hingedly fastened at its lower corners to the heads 55, to adapt it to open in an outward direction, the gate 61 consisting of a plate like the shelves 57 except that, instead of being provided with openings 58, it has formed in it, to register with said openings, U-shaped slots 62 extending transversely of the gate-plate from its free edge. Studs, each carrying anti-friction rollers 63 on its protruding ends, project transversely through the free ends of arms 64 pivotally supported on the opposite rack-heads and carrying pins 65 at which they are connected by stiff coiled springs 66 to the heads 55 at pins 67 projecting therefrom; and the rollers 63 on the inner ends of the studs work in rigid arch-shaped loops 68 on opposite ends of the gate.

On the trough 25, adjacent to the delivery side of the soaker, is supported the chute 69, the preferred construction of which is most clearly illustrated in Figs. 15 to 17, inclusive. The outer surface of the chute is provided at intervals, to register with the gate-slots 62, with longitudinal grooves 70 of V-shape in cross-section, for guiding the bottles as they are released from the soaker, in the manner hereinafter described, into the rinsing trough, on which the chute is adjustably supported; and each guide-groove terminates at its lower end in a deflected extension 71 of the chute-base for checking the momentum of the bottles in discharging into the trough. To the flanges 72 which extend from opposite sides of the trough at their upper edges are secured the bearing-clips 73 containing the vertical slots 74, through which pass bolts 75 provided on their threaded ends with wing-nuts 76, these bolts also passing through openings 77 in the depending sections of angle-plates 78 provided in their top-sections with longitudinal slots 79, extending parallel with the lateral edges of the chute, for the passage through them of bolts 80 carrying wing-nuts 81 on their threaded ends and passing through openings 82 in the ends, which project beyond the sides of the upper part of the chute, of base-boards 83. By loosening the nuts 76 the chute may be raised and lowered on the clips 73, owing to the slots therein, and may be tilted to any desired angle relative to the delivery from the soaker, because of the openings 77 in the angle-plates 78, and tightening of the nuts fastens the chute in such adjusted position, and by loosening the nuts 81 the chute may, owing to the provision of the slots 79 in the angle-plates, be moved lengthwise nearer to or farther from the soaker, to be fastened in such adjusted position by tightening the nuts 81.

The machine operates as follows: With water in the tank and rinsing-trough, the circulating-pump 23 being in action and the drum-shaft 40 in motion, the shaft 44 is rotated to actuate the agitator, and the worm-gears are driven to slowly turn the shaft 39, 130

thereby causing the endless chains 52 and with them the racks to travel in the direction indicated by the arrow on Fig. 1. In this travel the gate of each rack in succession is 5 automatically opened, at the rear side of the machine, to permit the rack to be filled with bottles to be soaked, and thereupon similarly closed, while the gate of another rack is being opened at the opposite or delivery side 10 of the machine to permit the rack to discharge its load of soaked bottles to the chute 69, whereupon the gate closes automatically to be again opened to admit a fresh load of bottles to be soaked when the rack reaches 15 the loading position. These operations are effected by engagement with the cam-plates of the rollers 63. Thus, when a rack attains, at the delivery-side of the machine, the position of that represented in Fig. 9, relative to 20 the cam-plates 54, its gate is about to be opened. The opening begins when the rack attains the position represented in Fig. 10, wherein the rollers 63 engage the cams 54^a, whereby in the continued travel of the 25 chains 52 the rollers are arrested relative to such travel, and the stoppage causes their engagement with the cams, under their confinement in the loops 68, against which they bear, to open the gate against the resistance 30 of the springs 66. The first opening of the gate takes place when the base of the rack has been brought adjacent to the receiving-end of the chute, toward which the gate, when open, inclines downwardly to afford a 35 bridge leading to the chute. The bottles in the rack, thus freed from the retention exerted against their shoulder-portions by the margins of the gate-slots, through which latter the bottle-necks protrude, slide out of it, 40 across the bridging gate and down the guides of the chute, at the ends of which their momentum is checked or cushioned by the chute-ends 71, which direct the bottles, (one of which is indicated by dotted lines in Fig. 45 2) horizontally to float upon the surface of the water in the trough 25. The depth of the water to the false bottom in the trough is less than the length of a bottle, so that the bottle, in filling with the rinsing-water, can- 50 not sink in upright position entirely below the water-surface, but will assume, after floating for a time, an inclined position with one end resting on the false bottom and the other end projecting above the water-level, 55 where it is accessible for withdrawal by the attendant without requiring immersion of his hand into the water to grasp it, thereby facilitating the withdrawing operation. Any label or foreign matter that separates from 60 bottles in the rinsing-trough will drop through the interstices in the false bottom and lodge on the bottom of the trough, whence it may be readily removed when the trough is emptied of water through the opening 27. 65 In the continued travel of the rack it clears

the inner rounded ends of the cams 54^a, in attaining the position represented in Fig. 11 of riding the rollers along the straight backs of the cam-plates, which maintain the gate open until, in attaining the position represented of the rack in Fig. 12, the rollers reach the inclined upper ends 54^b of the cam-plates 54, in riding along which the recoil force of the springs 66 is permitted to act to close the gate on its pivotal ends or hinges, 70 the complete closure taking place after the rollers have cleared the extremities of the ends 54^b and have thus become entirely free from the cam-plates to permit the remnant of recoil-force of the springs to snap the gate 75 shut, this condition being shown in the dotted representation in Fig. 12. When the rollers 63 on a rack-gate encounter the cams on the upper ends of the rear cam-plates 54, the gate will be opened by that encounter, in 80 the manner described of the action of the forward cams 54^a, and will be kept open by the riding of the rollers along the vertical portions of the plates to enable the rack to be filled by an attendant with bottles to be 85 soaked; and when the rollers engage with and clear the lower inclined ends of the rear cam-plates, the gate will be gradually closed by the recoil of its controlling springs to confine the bottles while being soaked and until 90 they are released, as described, at the delivery-side of the machine. 95

The slow travel of the chains 52, under the motion of the worm-gear, retains the bottles in the tank sufficiently long for thoroughly 100 soaking them and removing from them most, if not all, of the labels, and the action of the water is materially enhanced by the agitator, the relatively fast speed of which throws the water more or less forcibly against the bottles 105 in the racks, which, as will be observed, are open to permit the free circulation of the water through them for its full access to the bottles. It should be mentioned in this connection that the racks occupy positions on 110 the endless carrier in which they extend at an angle of about thirty-two degrees, and the bottles enter the soaking-water at a pitch with the necks extending upwardly, 115 whereby they become filled with the water, while they emerge from the water with the necks extending downwardly and discharge their contained water before arriving at the point of delivery.

Among the more important distinguishing 120 characteristics of the present invention, besides those already referred to, the following may be mentioned: The racks form permanent parts of the soaker, not requiring to be removed for loading bottles into and discharging them from the machine; and the construction of the crate adapts it to receive and hold bottles of varying lengths within a wide range, without requiring adjustment of any part of the machine or of the crates 125 130

themselves to accommodate bottles of different sizes. Moreover, the construction of the crate adapts it to hold the bottles loosely whereby they are free to reciprocate longitudinally in their bearings between the stop 59 and gate under the action of the currents in the soaking-water produced by the agitator, and this movement of the bottles supplements the cleaning action upon them of 10 the water.

What I claim as new and desire to secure by Letters Patent is—

1. In combination, a bottle-soaking machine having a water-tank and a traveling carrier therein, with bottle-racks on the carrier, each comprising end-heads with a plurality of spaced partitions extending longitudinally between them and containing rows of bottle-openings alining in series transversely of the rack, a spring closed door hinged to the base of the front side of the rack, a stop for the bottle-bottoms on the rear side of the rack, means for automatically opening said door as the racks attain the 25 delivery point on the machine, a rinsing trough supported at the delivery side of the machine, and a bottle-chute leading from said side to the trough and toward the receiving end of which the opened door of the 30 rack attaining said point extends as a bridge.

2. In combination, a bottle-soaking machine having a water tank and a traveling carrier therein, with bottle racks on the carrier, each comprising end-heads with a plurality of spaced partitions extending longitudinally between them and containing rows of bottle-openings alining in series transversely of the rack, a door on the front side 40 of the rack containing bottle-neck openings coinciding with said alining series of openings, means for automatically opening said doors as the racks attain the delivery point on the machine, a rinsing trough supported 45 at the delivery side of said machine, and a bottle-chute leading from said side to the trough and toward the receiving end of which the opened door of the rack attaining said point extends as a bridge.

3. In combination, a bottle-soaking machine having a water tank and a traveling carrier therein, with bottle racks on the carrier each comprising end-heads with spaced shelves extending longitudinally between them containing alining openings for supporting the bottles at different points along their body portion, a stop on the rear side of the rack, a spring closed door hinged at the front side of the rack and containing slots 60 for the bottle-necks alining with said openings and extending in the door from its free edge, means for automatically opening said

door as the racks attain the delivery point on the machine, a rinsing trough supported at the delivery side of the machine, and a 65 bottle-chute leading from said side to the trough and toward the receiving end of which the opened door of the rack attaining said point extends as a bridge.

4. In a bottle-soaking machine, a bottle-rack supported to travel therein and comprising end-heads with spaced shelves extending between them containing alining openings for supporting the bottles, a stop-bar extending between the heads at the rear side of the rack, a gate at the front side of the rack hinged at its ends to said heads near their bases and containing slots for the bottle-necks alining with said openings, loops on the ends of the gate, arms pivotally supported on the gate-ends and carrying anti-friction rollers extending through said loops, springs connecting said arms to the rack-ends, and cams in the paths of said rollers for opening the gate against the resistance of 85 said springs.

5. In a bottle-soaking machine, the combination with a water-tank having a frame on its top, of sprockets journaled on said frame and in the tank to form vertically alining members, endless chains connecting said members, a drive-shaft geared to said sprockets, and bottle-racks extending at intervals between and permanently connected with said chains, each rack being open to the free 95 circulation through it of the soaking-water and having a spring-closed gate containing slots for the bottle-necks hinged upon it to open in the direction contrary to that of the travel of the rack and form a bridge when 100 open, confined anti-friction rollers extending from the gate-ends, and cam-plates on said frame in the paths of said rollers and each having a cam on one end and an outwardly inclined opposite end.

6. In combination, a bottle-soaking machine having a water-tank and an endless traveling carrier therein, with bottle-racks on the carrier each having a bottle-confining spring-closed door hinged at the base of the 110 rack and containing slots for the bottle-necks, means for automatically opening said doors as the racks attain the delivery-point on the machine, a rinsing-trough supported at the delivery-side of said machine, and a 115 bottle-chute leading from said side to the trough and toward the receiving-end of which the opened door of the rack attaining said point extends as a bridge.
